UNITED STATES PATENT OFFICE

2,570,580

FUEL-SAVING HOT-AIR FURNACE

Alfred E. McClure, Marne, Mich.

Application March 14, 1949, Serial No. 81,360

2 Claims. (Cl. 126—99)

1

This invention relates to a fuel-saving furnace. An object of the invention is the production of a furnace which will greatly prevent the loss of heat, and thereby produce a great amount of saving in fuel and costs.

Another object of the invention is the novel construction of a furnace which will utilize the maximum amount of heat in the fuel.

A still further object of the invention is the improvement of the construction of the furnace in which the fire contacts a greater radiation surface, which enables a maximum amount of hot air to be produced by a relatively small amount of fuel consumed.

Another object of the invention is the construction of a furnace which has an efficient radiator construction, including the general fire-box construction, whereby a highly efficient heating system is produced.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a view showing the preferred type of the furnace in vertical central section.

Figure 2 is a horizontal sectional view, taken on line 2—2, Fig. 1, and looking in the direction of the arrows.

Figure 3 is a fragmentary vertical sectional view of another embodiment of this invention.

Figure 4 is a fragmentary view of the embodiment shown in Figure 3, partly shown in elevation and partly shown in vertical section.

Figure 5 is a fragmentary vertical sectional view of the furnace shown in Figures 3 and 4.

Referring to the drawings, in which the preferred embodiment of the invention is illustrated, in Figures 1 to 3, 1 designates the vertical furnace casing, which is enclosed by jacket 2. Extending partly around the furnace casing 1 is a radiator 3, which is positioned near the bottom of the furnace casing 1. This radiator is divided by a horizontal partition 4 into an upper compartment 5 and a lower compartment 6. As seen in Fig. 3, the partition 4 terminates short of the outer ends of the radiator 3, whereby smoke and gases can pass from compartment 5 into compartment 6 and thence out through smoke pipe 7 into the chimney 8. On the outer ends of the substantially U-shaped radiator 3 (Fig. 2) are cleanout doors 9. The furnace jacket 2 is provided with a cold air inlet 10, Fig. 1, and is also provided with an ordinary ash door 11, whereby

2

access to the ashpit may be secured. It is to be understood that cold air entering the furnace at the air inlet 10, Fig. 1, will be heated and after which it will enter pipe 21a.

5 The furnace casing 1 is also provided with a fuel door 12, whereby access to the fire-box 13, Fig. 1, is obtained.

A plurality of hollow, vertical ribs 14 are provided. A vertical tube 15 is integral with each 10 side of a respective rib 14. The lower ends of the ribs 14 are closed by a plate-like member 14a. These tubes 15 open at their upper ends into the furnace casing 1 and communicate at their lowest ends with the upper compartment 5 of the radiator 3. The radiator 3 is supported by angle brackets 16 fastened to the side of the furnace casing 1. By reason of the efficient construction of the hollow, vertical ribs 14 and tubes 15, said tubes perform a dual function, to wit, they close 15 the space between the sides of the hollow ribs 14 and also conduct the smoke and gases from the interior of the furnace casing to the radiator 3. Further, this novel construction presents an increased area of metal for the flames and heat to 20 affect, thereby giving a greater amount of radiation surface, with a minimum amount of fuel being used.

Of course, it will be understood that the space 25 at the bottom between each two contiguous sides of each rib is closed by members 14a, so that no smoke or gases can pass downward, but must enter the tubes 15 to escape through the radiator 3 to the chimney 8.

In the embodiment shown in Figs. 3 to 5, the 30 same general structure is involved, with the exception that the radiator 3a is made of round or pipe-like portions. The upper pipe-like portion 17 opens into the lower pipe-like portion 18. A cleanout door 9 is provided for each end 35 of the radiator 3a.

As the radiator is at the bottom of the furnace, the cold air hits the bottom of the radiator first, which cools the contents of the lower compartment of the radiator before it enters 40 the chimney. This radiator will be cool all the time, causing a great saving in fuel. Therefore, the heat loss should be less than 10%.

In the round or pipe-like structure of the 45 radiator 3a the result will be highly satisfactory because the radiator is divided by a space 19, Fig. 5, leaving only the forward end 20 closed.

The fire-box 13 and grate 21 may be of any 50 desired construction that will cooperate with the rest of the elements of this furnace for the best possible results.

The jacket 2 provided with a hot air outlet

service pipe 21a, Fig. 1. The radiator 3a is of a substantially U-shaped structure, the same as radiator 3.

While I have described the preferred embodiments of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In a furnace of the class described, the combination with a vertical furnace casing having a fire-box, of a horizontal, substantially U-shaped radiator partly around the lower portion of said fire-box, said radiator provided with upper and lower communicating compartments, brackets fastened to said furnace casing and being under and supporting said radiator, said furnace casing provided with cleanout means at the ends of said radiator, said casing provided with a fuel door above said radiator, said furnace casing provided with outwardly-extending hollow, vertical ribs, means forming a vertical tube integral with each side of a respective rib, a jacket provided with an outlet pipe enclosing said furnace casing, and said tubes opening at their upper ends into said furnace casing and at their lower ends into said upper compartment of said radiator.

2. In a furnace of the class described, the combination with a vertical furnace casing, a fire-box in said furnace casing, a jacket surrounding said furnace casing, of a U-shaped radiator partly around said fire-box, said radiator including upper and lower communicating compartments, said furnace casing including outwardly-extending vertical hollow ribs, means forming a vertical tube integral with the sides of a respective rib and closing the space between said sides at their rear portions, said tubes communicating at their upper ends with the interior of said furnace casing and at their lower ends with said upper compartment of said radiator, and an outlet pipe on said jacket and in communication with the interior of said jacket.

ALFRED E. MCCLURE.
